UNITED STATES PATENT OFFICE.

HERMANN A. KLEMM, OF NEW YORK, N. Y., ASSIGNOR TO AMELIA HESSEL, OF BOROUGH OF BRONX, NEW YORK, N. Y., AND SOPHIE HESSEL, OF SHELDON, CONNECTICUT.

DOUBLE-ZIGZAG SEWING-MACHINE.

SPECIFICATION forming part of Letters Patent No. 686,662, dated November 12, 1901.

Application filed January 21, 1901. Serial No. 44,127. (No model.)

To all whom it may concern:

Be it known that I, HERMANN A. KLEMM, a citizen of the United States of America, and a resident of the city of New York, borough of Bronx, county of Westchester, and State of New York, have invented certain new and useful Improvements in Double-Zigzag Sewing-Machines, of which the following is a specification.

My invention consists of appliances to sewing-machines for producing flat fancy or ornamental and very elastic seams by the use of two needles each carrying its thread and suitable under thread mechanisms for chaining or locking the needle-threads, whereby on the upper surface two parallel rows of stitches are formed at a suitable distance apart, with diagonal or zigzag loops of each extending from one to the other of the parallel rows, so as to form a double-zigzag seam in which the diagonal loops cross each other at the middle line between the two rows of stitches, the arrangement being such that exchange of the needles is effected without turning the needles, whereby the relations of the needles of the looping device are unchanged and a single looper working in the plane of the two needles may bind off the loops of both needles, said seams being especially useful in uniting elastic knit fabrics.

In this example I represent a couple of needles placed side by side in a line at right angles to the feed-line, with means for causing them to exchange places with each other at each operation for laying the diagonal loops extending from one line of stitches to the other and so that they thus cross each other, and I have chosen a machine of common construction in respect to main parts and have contrived the appliances for my purposes as suited to such a machine, but will modify them in future constructions and for adaptation to other machines as may be required.

My invention is, as embodied in the present machine, represented in the accompanying drawings, in which—

Figure 1 is a side elevation with the bed-plate in section. Fig. 2 is a detail showing one of the needle-bars and part of the crank mechanism for operating it in elevation. It also shows the supporting-frame for the nee-

dle-bar in vertical section. Fig. 3 is a transverse section of the machine on line 3 3 of Fig. 1. Fig. 4 is a front elevation with a section of the bed-plate on line 4 4 of Fig. 1. 55 Fig. 5 is a detail of the needle-bar of Fig. 2 and its supporting and operating mechanism in front elevation. Fig. 6 is a plan view of the complete machine. Fig. 7 is a detail showing the two needle-bars in horizontal 60 section, also a horizontal section of the supporting-frame of Fig. 5 and plan view of part of the needle-bar-operating gear. Fig. 8 is a detail showing the two needle-bars in horizontal section and a plan view of a laterally-projecting arm of one of the needle-bars on which the needle is mounted instead of being mounted directly on the bar. Fig. 9 is a plan view of the presser-foot, showing the needle-holes and the slot for affording clearance for 70 the needle-threads. Fig. 10 is a detail of the throat-plate, showing the feed-slot, needle-holes, and clearance-slots for the needle-threads. Figs. 11 to 17, inclusive, are perspective views showing the seam and illustrating the operations of the needles and the looping-hook when the hook is adapted for binding both needle-threads. 75

The needle *a* is mounted in the lower end of the needle-bar *b* in the usual manner; but the needle *c* is mounted near the extremity of a laterally-projecting arm *d* of the needle-bar *e*, the plane in which the two needles stand being at right angles to the feed-line, the direction of which is indicated by the 85 presser-foot *B* in Figs. 1 and 4. (See Fig. 8 for further illustration of the relations of the needles and their bars.) The needles change places with each other after rising clear of the work successively and before descending 90 into the work again to cross the threads from one line of stitches to the other on the upper surface of the material and to cross the threads intermediately of said lines, and thus form the double-zigzag stitch shown in Figs. 11 to 95 17, inclusive. This is the essential feature of the invention and can be accomplished in various ways, one of which (shown herein for illustration) is contrived as follows; but I do not limit my claim to any particular way. 100

In Figs. 1 and 8 the needles stand in the position for beginning their work. They are

first thrust down through the work for engagement of their threads by the looper. In this case it is a single looping-hook *f*, working in the plane of the two needles, or it may 5 be a shuttle. When after their threads are thus engaged the needles rise again above the work, the needle-bar *b* shifts downward relatively to the lower margin of the drawing (see Fig. 8) far enough to clear the 10 extremity of arm *d*, which then moves leftward into the position vacated by bar *b*, and bar *b* shifts to the right hand and upward as to the drawing into the position for substituting its 15 needle for the needle *c*. Then the needles make another stroke through the work and retire, as before, and the needles shift back again into their original positions. With these outlines of the changing operations of the needles stated at the outset the contrivances of apparatus for effecting them, which 20 will now be described, will be more easily understood.

The needle-bar *b* is mounted so as to reciprocate vertically in a frame *r*, which is carried in another frame *g*, pivoted at *h* on the left hand of the front face of the machine-head *i*, so as to swing like a gate toward and from the face of said head and is also so arranged in said gate as to slide radially to the 25 pivots of the gate. Said frame *r* has a lateral arm *j* projecting from the right-hand side, which is coupled by a connecting-rod *k* with a rocking arm *l*, projecting upward from the pivot *m* and having a stud-pin *o*, working in the groove *n* of a cam-disk *p* for rocking arm *l* to swing the needle-bar *b*. The cam-disk *p* is geared by a pair of bevel-wheels *q* with the main shaft *s*.

As the needles shift only one way to each 30 complete circle of the rest of the machine, the wheels *q* for operating the cam-disk *p* are proportioned for one revolution of it to two cycles of the rest of the machine.

For sliding the needle-bar-supporting frame 35 *r* in the gate-frame *g* said frame *r* is coupled by a link *t*, pivoted to it at *u*, with a lever *v*, pivoted to the machine-head at *w* and geared by the stud *x* with the cam-groove *y* in the disk *z*, carried on the shaft 2, which is geared 40 by the wheel 3 and one of the bevel-wheels *q* on the main shaft *s*. This gives the lateral motions to needle-bar *b* for clearing arm *d*, and the gate-frame gives the motions for traversing the feed-line, the course of which motions combined is indicated by the dotted line 45 4, Fig. 8. The needle-bar *e* is also mounted in a swinging frame 5 for shifting needle *c* forward and backward from side to side of the seam, said frame being pivoted to the 50 machine-head at 6 on the right-hand side, and it is coupled at its other side by the connecting-rod 7, pivoted to it at 8, with another rocking arm 9 on the same pivot *m* that carries the rocking arm *l*, but projecting downward, while arm *l* projects reversely, so that 55 the needles are always shifted reversely to each other.

The motion for reciprocating the needles vertically is communicated from the main shaft *s* first to needle-bar *b* by the connecting-rod 10 on the crank-pin 11 and coupled with the stud-pin 12 of a collar 13, fixedly attached to the needle-bar, the stud-pin 12 being free to play in the eye of the connecting-rod as the needle-bar *b* shifts forward and backward in crossing from side to side of the seam. From this needle-bar *b* motion is communicated to the other bar *e* by means of the block 14, rigidly secured to bar *b* just above collar 13 and having the horizontal slot 15, 60 in which a stud 16 of a collar 17, rigidly secured to bar *e*, is engaged, so that bar *e* is made to work in unison with bar *b*. The slot 15 permits the lateral play of frame *r* relatively to said stud 16, and the length of the 65 stud is adapted to maintain due connection of it with block 14, subject to the swinging motions of the bar-carrying frames *r* and 5; but any other means of transmitting the motion from one needle-bar to the other may be 70 employed, or the needle-bars may be operated by independent levers, one for each, in the usual way.

The presser-foot *B* has two perforations 18, through which the needles work, between 75 which is an A-shaped slot 19, through which the crossed needle-threads run, and the stitches are drawn up when the work feeds along. The throat-plate 20 also has like needle-holes 21, connected by slots 22 with the feed-slot, through which the needle-threads 80 also escape.

A long hook *f* is employed and arranged to work transversely to the line of the feed for binding both the needle-threads. It is arranged on the pivot 24 for swinging forward through the needle-thread loops and backward for casting them off and is connected by the rod 25 and pin *D* with the crank-pin 26, operated by the shaft 27, for so operating 90 it, and the pivot 24 is carried on the end of the rock-shaft 28 for the lateral movements of the hook relatively to the needles, whereby it passes them on one side to engage the needle-loops and after the partial rise of the 95 needles shifts to the other side of the needles for opening the loops to the needles as they descend again, said rock-shaft 28 having a crank-arm 29 on its rear end, which has a stud 30, engaging a cam-groove 31 in a hub 100 of shaft 27, to be operated so as to impart the said lateral movements to the hook. The shaft 27 is geared by a pair of bevel-wheels 32 with a vertical shaft 33, located in the vertical part 34 of the hollow stationary arm 105 35, and geared at its upper end with the main shaft *s* by a pair of bevel-wheels 36, dotted in Fig. 6; but the hook and the means of operating it, also the feed-operating lever 37, are common to the machine which I have taken 110 for the application of my improvements and are not claimed herein.

Although the operations of the looper relatively to the two needles for securing the

needle-threads is the same as in other machines, especially the one represented in the patent to L. Muther, January 29, 1886, No. 344,492, the said operations are herein illustrated in Figs. 11 to 17, inclusive, for the better understanding of the operations of the interchanging needles in producing the double-zigzag seam of my invention.

With the material 37, in which the seam has progressed several stitches and supposed to be lying on the work-plate, (not shown), and the two needles descending for the beginning of a new stitch, the material having been fed along preparatory therefor, the looper 7 will occupy the position represented in Fig. 11, with the loops 38 of the respective needle-threads on it, the needles will descend on the rear side of the looper and through the loop 39 of the looper-thread which was passed through loops 38 of the needle-thread on the forward movement of the looper, as represented in Fig. 12. The looper then withdraws and the needles having completed the downward movement and passed upward to some extent throw out new loops 38 of needle-thread, as represented in Fig. 13, when the looper swings forward again behind the needles and through the needle-loops, as in Fig. 14. The needles then rise out of the work, drawing the needle-threads up on the looper, as shown in Fig. 15, and the material will then be fed along preparatory to the beginning of new stitches, as in Fig. 16, and at the same time the needles exchange places, as hereinbefore described, for crossing their threads on the upper surface of the material, as also shown in Fig. 16, when the work proceeds as before for making the next stitch of each row, when the needles reverse again. Fig. 17 represents in perspective view a short chain of the seam separately from the material, showing the loops 38 of the needle-threads secured by loops 39 of the looper-thread. In Figs. 11 to 17, inclusive, the double-zigzag seam is shown on the surface of the material 37 by the two needle-threads crossing from one row of stitches 40 to the other row 41 diagonally and crossing each other intermediately of said rows at 42 and looped through the material, as shown.

It is to be understood that this improved machine is to be used alike for uniting two or more pieces of goods and for ornamental seams on the surfaces of single pieces.

55 What I claim as my invention is—

1. In a sewing-machine, the combination of needle-operating and feed-operating mechanisms, two needles mounted independently of each other and independently movable laterally relative to each other and located in a line transversely to the feed-line and at a suitable distance apart, and each having its in-

dividual thread, means to cause said needles to automatically exchange places with each other while in the operation of sewing without turning the needles, and means for binding the needle-thread loops. 65

2. In a sewing-machine, the combination of needle-operating and feed-operating mechanisms, two needles mounted independently of each other and independently movable laterally relative to each other and located in a line transversely to the feed-line and at a suitable distance apart and each having its individual thread, means to cause said needles 70 to exchange places with each other alternately with the stitch-forming operations without turning, and means for binding the needle-thread loops.

3. In a sewing-machine, the combination of needle-operating and feed-operating mechanisms, two needles mounted independently of each other and located in a line transversely to the feed-line and at a suitable distance apart and each having its individual thread, 75 means to cause said needles to exchange places with each other alternately with the stitch-forming operations without turning, and a looping device working in the plane of the needles for binding off the loops of both 80 needle-threads.

4. In a sewing-machine, the combination of needle-operating and feed-operating mechanisms, two needles located in a line transversely of the feed-line and at a suitable distance apart and each having its individual thread, both having automatic translatory movements for exchanging places one with the other while in the operation of sewing, one of which moves in a direct line from one 95 position to the other, and the other moves in a curved path between said positions to avoid conflict of the needles one with the other and means for causing such translatory movements. 100

5. In a sewing-machine, the combination of needle-operating and feed-operating mechanisms, two needles located in a line transversely to the line of feed, a support for one of said needles having translatory movements 110 carrying it laterally out of one working position and reversely into the other working position, a support for the other needle having translatory movements in a direct line from one working position to the other, and means 115 for simultaneously operating said supports and thereby exchanging the positions of the needles.

Signed at New York city this 19th day of January, 1901.

HERMANN A. KLEMM.
